UNITED STATES PATENT OFFICE.

WALTER C. MITCHELL, OF ST. LOUIS, MISSOURI.

SMOKE CONSUMER.

Application filed July 6, 1925. Serial No. 41,585.

- This invention relates to smoke consumers. An object of the invention is to provide an apparatus for passing combustion products emitted by furnaces, kilns and the like 5 through a spray in the novel and efficient manner hereinafter disclosed to remove the carbon and other obnoxious substances from the combustion products prior to its discharge into the open air.
- 10 Another object of the invention is to provide the efficient means hereindisclosed for washing the combustion products to remove therefrom the heavy substances so that the products of combustion will be ultimately 15 discharged without such elements and thus freed from objectionable characteristics.
- Other objects of a specific nature will appear from the following description, reference being made to the drawings in 20 which—
- Fig. 1 is a view with parts in section showing a satisfactory embodiment of the invention.
- Fig. 2 is a sectional view on the line 2—2 25 of Fig. 1.
- Fig. 3 is a view on the line 3—3 of Fig. 1 looking in the direction of the arrows.
- Fig. 4 is an enlarged detail view showing a connection of a flue or pipe from the furnace or kiln with the washing apparatus.
- 30 Fig. 5 is a sectional view on the line 5—5 of Fig. 1.
- Fig. 6 is a sectional view showing a modification and may be considered as taken on a 35 section similar to the line 2—2 of the structure shown in Fig. 1.
- Fig. 7 is a cross section showing a portion of one of the walls of the modification taken on the line 7—7 of Fig. 6.
- 40 Fig. 8 is a view partly in section showing an alternative form of connection from the furnace or kiln with the washing apparatus.
- Fig. 9 is a sectional view on the line 9—9 45 of Fig. 8 showing a form of damper.
- Fig. 10 is a view showing a gate or valve forming a part of the water seal of the device which may be opened to permit removal of the floating substances removed from the combustion products.
- 50 While the invention is shown in connection with a kiln 1 for use in the manufacture of brick or fire clay products, the invention is not restricted to use with such products but may be satisfactorily used in 55 connection with other combustion apparatus.
- As shown a pipe or flue 2 from the kiln 1 extends loosely through a part 3 of the top wall of the kiln and is capable of oscillation or inclination with the settling or change of position of any of the contents of the kiln which contact with the lower end of said pipe or flue 2. The pipe or flue 2 is preferably provided with an opening in one side (Figs. 1 and 5) which may be opened and closed by an air draft door 4 hinged to the pipe or flue and held in closed position by a releasable catch 5.
- The upper end of the pipe or flue 2 extends through the wall of and into a pipe 6 surrounded by a flange 8 extending into the pipe 6 and having its inner extremity flared away from the pipe or flue 2, permitting the latter to tilt or incline in conformity with the change of position of any of the contents of the kiln contacting with the opposite end of said pipe or flue 2. This prevents opening of the joint connecting the pipes 2 and 6 and has been found highly useful in connection with kilns. A water pipe 7 controlled by a valve 8^a extends longitudinally through the upper portion of the pipe 6 and in said pipe 6 is provided with numerous spray nozzles 9, so that the combustion products discharged into the pipe 6 will be subjected to the action of the sprays 85 from said nozzles and a considerable portion of the obnoxious substances, such as carbon, will be washed and removed from the combustion products.
- From the pipe 6 the combustion products 90 are discharged into an enclosure 10 preferably through the top wall thereof. A number of water pipes 11 extend into the enclosure 10, certain of said pipes 11 having upwardly directed spray nozzles 12, and another of said pipes 11 having downwardly directed spray nozzles 13. The spray nozzles 12 and 13 are preferably arranged in series, two series of said nozzles being separated by a downwardly extending partition 14, and other series of said spray nozzles being separated by an upwardly extending partition 15. The partition 14 terminates above the bottom of the enclosure 10 so that the combustion products from the pipe 6 105 passes downwardly in the space between the partition 14 and one wall of the enclosure 10, during such movement being subjected to the action of the sprays in said space; and thence under the lower end of the partition 14 and upwardly through the space between the partitions 14 and 15 in which space the 110

combustion products is subjected to sprays in said space, and from said last named space over the upper end of the partition 15 into the space between the partition 15 and the adjacent wall of the enclosure 10; and thence downwardly in said last named space through the sprays therein to an outlet pipe 16 which, in the embodiment shown in Fig. 1, is connected with an air pump or fan 17 functioning to maintain continuous movement of the combustion products thereto. The lower end of the partition 14 is preferably provided with diverging baffles 18 which tend to deflect and cause the combustion products to pass through and be subjected to the action of the sprays. Similarly, the wall of the enclosure 10 has a baffle 19 adjacent to the opening into the pipe 16 and functioning to prevent formation of a stream or reduced current of combustion products to said pipe 16; all with the result that the combustion products are properly subjected to the action of the sprays.

From the fan or air pump 17 the fumes withdrawn from the enclosure 10 are discharged through a pipe 20, and wherever needed or required said pipe 20 may discharge into an additional enclosure 21 having a tortuous passage formed by an upwardly extending wall 22 terminating short of the top wall of the enclosure, and a downwardly extending wall 23 terminating above the bottom of the enclosure. Pipes 24 extend into the enclosure 21, certain of which pipes are equipped with upwardly directed spray nozzles 25 and another of which pipes is equipped with downwardly directed spray nozzles 26, so that as the combustion products or fumes pass through the tortuous passage as indicated by the arrows, they are subjected to the action of the sprays and the remaining obnoxious elements are removed. The downwardly extending partition 23 has diverging baffles 27 near its lower end, causing the combustion products to be subjected satisfactorily to the action of the sprays. From the end of the tortuous passage in the enclosure 21 the clarified smoke is discharged through an outlet pipe or flue 28, adjacent to the opening into which a baffle 29 is provided to insure proper movement of the smoke through the sprays.

The side walls of each of the enclosures 10 and 21 terminate in basins comprising vertical outer walls 30 having their ends connected to extensions 31 of the end walls of the enclosures 10 and 21, respectively. The inner walls 32 of said basins converge upwardly and inwardly to intersection forming a longitudinal divider 33, causing the spray deposits to pass in approximately equal proportions to the two side basins. An outlet or overflow pipe 34 is provided for each side basin and open therefrom above the planes of the lower ends of the

side walls of the enclosures 10 and 21, so that the lower ends of said side walls are immersed in water which provides a seal. Drain pipes 35 open near the bottoms of the basins for draining off the contents thereof and are equipped with valves 36. Screens 37 connect the basin walls 30 with the lower portions of the side walls of the enclosures 10 and 21, respectively, to prevent the accumulation of deposit from the outside into said basin. 70 75

In the alternative structures shown in Figs. 6 and 7, the side walls of the spray enclosures 38 which corresponds to either of the enclosures 10 or 21 have their inner sides provided with vertical corrugations 39 which increase the inner surface area of the walls providing wet surfaces of larger area, to the action of which the passing combustion products is subjected. In addition, the vertical partitions 40, corresponding to the vertical partitions shown in Fig. 1, the enclosure 38 has within the tortuous passage formed by said partitions and by the end walls of the enclosure, a number of baffles 41 inclining inwardly and downwardly from the side walls of the enclosure, one series of such baffles near the top and another series near the bottom of the enclosure. In addition, an inverted V-shaped baffle 42 is located between the upper and lower series of baffles 41. Water is supplied to the enclosure through pipes 43, certain of which have upwardly directed nozzles 44 and another of which has downwardly directed nozzles 45. The same reference numerals are applied to the remaining parts of Fig. 6 which are identical with parts indicated by the same reference numerals in the preceding views of the drawings.

Fig. 8 shows an alternative form of connection from the kiln or furnace with a spray pipe 46 corresponding to the spray pipe 6 previously described. As shown a flue structure 47 leading from the kiln or furnace is equipped with an air draft control device 48 and has a flue extension 49 opening into a pipe 50 leading to a connection 51 opening into the pipe 46. The lower end of the pipe 50 is imbedded in granular or pulverized material 52 in a basin 53 formed around the outlet 49. The pipe 50 is provided with a damper 54.

As shown in Fig. 8 there are series of pipes 50 opening into opposite sides of the spray pipe 46 and serving adjacent series or rows of kilns. A water pipe 55 corresponding to the water pipe 7 extends through the pipe 46 and has spray nozzles 56 in connection therewith. 120

A water pump 57 of any appropriate commercial construction may be used to force water through the water pipes and through the spray nozzles to produce the sprays. If desired a single motor 58 may have its shaft 130

59 operatively connected to drive both the fan or air pump 17 and the water pump 57. As shown, the fan device 17 may be used to withdraw the combustion products from the 5 tortuous passage in the enclosure 10 and to discharge the remnants of the combustion products into the tortuous passage in the enclosure 21, and the water pump 57 may be used to force water through all of the spray 0 devices embodied in the apparatus, a single motor serving to operate both the fan and the water pump.

As shown in Fig. 10 the water seal at the lower edges of the side walls of the enclosures may comprise a gate or valve 60 which is capable of vertical sliding movements and which, in its lower position, has its lower edge immersed in the water. When the gate or valve 60 is raised access may be had 20 to the interior of the enclosure through the elongated opening 61, permitting the floating substances to be skimmed off, while the settling may be withdrawn through the pipe 35.

25 From the foregoing it is apparent that my invention obtains all intended objects and purposes of eliminating the obnoxious elements from the fumes resulting from combustion of coal or other fuel, and discharges the unobjectionable fumes to the atmosphere. The combustion products may be caused to pass through as many spray enclosures as desired or as needed to obtain proper results. The invention may be 35 varied in numerous other particulars than those specifically stated. I do not restrict myself unessentially, but what I claim and desire to secure by Letters Patent is:—

1. An apparatus of the character described comprising a spray pipe, a pipe from 40 a source of combustion products supply having a flexible joint opening into said spray pipe, means for producing sprays in said spray pipe, an enclosure into which said spray pipe opens, elements forming a tortuous passage in said enclosure, means for producing sprays in said passage, a device for drawing the combustion products through said enclosure, a tortuous passage receiving the combustion products from said 50 device, and means for producing sprays in said second tortuous passage.

2. An apparatus of the character described comprising a spray pipe, a pipe from 55 a source of combustion products supply having a flexible joint opening into said spray pipe, means for producing sprays in said spray pipe, an enclosure into which said spray pipe opens, elements forming a tortuous passage in said enclosure, means for producing sprays in said passage, a device for drawing the combustion products through said enclosure, a tortuous passage receiving the remnants of the combustion 65 products from said device, means for pro-

ducing sprays in said second tortuous passage, an outlet pipe from said second tortuous passage, and a baffle device adjacent to the opening to said outlet pipe from said second tortuous passage.

3. An apparatus of the character described comprising an enclosure, upwardly converging inclined walls extending into the lower end of said enclosure, means cooperating with said walls to form a water seal 70 for the lower end of said enclosure, elements forming a tortuous passage in said enclosure, a pipe for admitting combustion products into one end of said passage, a device for withdrawing the remnants of said combustion products from the opposite end of said passage, means for producing sprays in said passage, an additional enclosure receiving the remnants of said combustion products from said device and having a tortuous 75 passage therethrough and a discharge outlet therefrom, and means for producing sprays in said second tortuous passage in said second enclosure.

4. An apparatus of the character described comprising an enclosure having upwardly converging bottom walls and side walls having their lower ends spaced from said bottom walls, means cooperating with said bottom walls to confine a quantity of 80 water of sufficient depth to immerse the lower ends of said side walls and forming a water seal therefor, elements in said enclosure forming a tortuous passage therethrough, means for producing sprays in said 85 passage, means for admitting combustion products into one end of said passage, and means for conducting remnants of said products from the opposite end of said passage.

5. An apparatus of the character described comprising an enclosure having upwardly converging bottom walls and side walls having their lower ends spaced from said bottom walls, means cooperating with 90 said bottom walls to confine a quantity of water of sufficient depth to immerse the lower ends of said side walls and forming a water seal therefor, elements in said enclosure forming a tortuous passage therethrough, means for producing sprays in said 95 passage, means for admitting combustion products into one end of said passage, and means for conducting remnants of said products from the opposite end of said passage.

6. An apparatus of the character described comprising two spaced enclosures, a pipe for admitting combustion products into one end of said enclosures, pipe connections for conducting remnants of the combustion products in the opposite end of said first enclosure into one end of the other 105 enclosure, a device in connection with said 110

- pipe connections for drawing said remnants of combustion products from said first enclosure and forcing said remnants into said second enclosure, means for producing sprays in each of said enclosures, spray deposit receptacles along the lower sides of said enclosures, and means controlling withdrawal of spray deposits from said receptacles.
- 10 7. An apparatus of the character described comprising a pair of adjacent tortuous passages having lateral openings at their lower sides, mechanism for drawing combustion products from one of said passages and forcing said products into the other of 15 said passages, a water seal device closing said lateral openings of each of said passages, mechanism for injecting sprays into each of said passages, and inclined bottom walls for conducting the spray deposits into 20 said water seal devices.

WALTER C. MITCHELL.
